UNITED STATES PATENT OFFICE

ALFRED JAMES TURNER AND RICHARD QUANTOCK, OF SOUTH BRISBANE, QUEENSLAND, AUSTRALIA

FUEL-LINE VALVE

Application filed May 11, 1929. Serial No. 362,350.

This invention relates to new and useful improvements in carburetors.

An object of the invention comprehends the provision of an air valve operable in conjunction with a butterfly valve of the carburetor.

Another object of the invention consists of a bypass port in the carburetor to admit air to the cylinders of the engine when same is coasting in gear with the butterfly valve closed and the ignition cut off, to provide an air brake and to carry off the usual gaseous fumes from the motor.

With the above and other objects in view, the invention further consists of the following novel features and details of construction, to be hereinafter more fully described, illustrated in the accompanying drawings and pointed out in the appended claim.

20 In the drawings:—

Figure 1 is a fragmentary side elevation of a motor vehicle engine and carburetor illustrating the application of the invention therewith.

25 Figure 2 is a top plan view of the invention.

Figure 3 is a longitudinal sectional view taken on line 3—3 of Figure 2.

Figure 4 is a detail sectional view taken on 30 line 4—4 of Figure 3.

Figure 5 is a horizontal sectional view taken on line 5—5 of Figure 3.

Referring to the drawings in detail wherein like characters of reference denote corresponding parts, the reference character 10 indicates a relatively thick gasket interposed between the neck 11 of the engine intake manifold 12 and the discharge port 13 of a carburetor 14, in the manner suggested in 35 Figures 2, 3 and 4 of the drawings.

A tubular extension 15, carried by and upwardly and obliquely disposed from the gasket 10, is exteriorly threaded for engagement with the adjacent end of a sleeve member 16. Said sleeve is joined to a coupling 17 at its opposite end secured upon the inner face of the vehicle instrument panel 18. A control rod 19, passing through the bore of 40 the sleeve member 16, passes through the bore

of the tubular extension 15 into the port 20 in the gasket 10.

A butterfly valve 21 is provided with horizontally disposed enlarged portions 22 upon diametrically opposite sides thereof and providing a pocket or bore 23 therebetween. That portion of the control rod 19, extended through the bore 23 in the butterfly valve 21, is shaped in conformity with said bore and held against independent sliding movement between the portions 22 through the instrumentality of a set screw 24.

The remaining depending extremity of the throttle rod 19 is projected outwardly and beyond the gasket 10 and which carries thereon a compression spring 25 and adjusting elements 26 therefor, the purpose of which will be presently apparent. A boss or stop collar, such as indicated at 27, carried upon the aforementioned projecting portion 70 of the control rod 19, is engageable at one end thereof with the uppermost end convolution of the compression spring 25 as best shown in Figure 3 of the drawings.

A set screw 28 carried by the boss 27 terminates to provide a stud 29 receivable within a longitudinally disposed slot 30 in the adjacent portion of the control rod 19 to provide a wear or thrust adjustment and purchase for the aforementioned end of the compression spring.

A disk 31, carried by and right angularly disposed upon the innermost end of the boss 27, has ports 32 adapted for selective registration with passageways 33 in the body of the gasket 10; the latter being joined for communication with a bypass or port 34 located immediately behind the butterfly valve 21 when the latter is shifted to occupy a closed position, as substantiated from the illustration of our invention in Figure 4 of the drawings.

Under ordinary running conditions, the ports 32 in the disk 31 will be disposed out of line and registration with the passageways 95 33 whereby the fuel mixture drawn up through the intake manifold into the combustion chambers of the engines will not be qualified by the mixing of excess air therewith. When coasting down hills in gear with the 100

control rod shifted to closed position, to dispose the butterfly valve horizontally and across the bore 20 of the gasket 10, with the ignition shut off, the ports 30 will be aligned with the passageways 33 in the body of the gasket 10 to admit air therethrough subsequently passing through the bypass or port 34 through the intake manifold 11 and into the combustion chambers of the engine, upon the suction strokes of the pistons therefor.

10 The compression strokes of each of the pistons in the bores of the cylinders will compress the admitted column of air and force same through the exhaust manifold and muffler whereby gaseous fumes will be discharged and the motor cooled off during journey down hill. Each of said cylinders, upon the compression strokes of each of the pistons therefor, will create separate and distinct snubbing actions and which will, in effect, provide a brake for the vehicle whereby the latter's service brakes and emergency brake may be saved.

15 If desired, a lock, such as indicated at 35, may be employed for the purpose of locking the butterfly valve 21 in closed position, upon the instrument panel 18 whereby unauthorized use of the particularly equipped vehicle will be prevented.

20 The invention is susceptible of various changes in its form, proportions and minor details of construction, and the right is herein reserved to make such changes as properly fall within the scope of the appended claim.

25 Having thus described the invention, what is claimed is:—

30 An attachment for use upon carburetors of internal combustion engines comprising a gasket of relatively thick formation, a butterfly valve mounted within the bore of the gasket, said gasket having a multiplicity of passageways in communication with a common bypass port leading into the bore of the gasket adjacent the discharge end of the butterfly valve, a disk included upon the gasket having ports selectively aligned with the passageways, and a control rod common to both the butterfly valve and washer to facilitate synchronization in the closing of the butterfly valve and the admission of air through the passageways and bypass port into the combustion chambers of the engine.

35 In testimony whereof we affix our signatures.

40 ALFRED JAMES TURNER.
RICHARD QUANTOCK.
